DESIGN FOR A RATTLE

Paul E. Allen, Skokie, Ill.

Application September 4, 1944, Serial No. 115,195

Term of patent 14 years

(Cl. D34—15)

To all whom it may concern:

Be it known that I, Paul E. Allen, a citizen of the United States, residing at Skokie, in the county of Cook and State of Illinois, have invented a new, original, and ornamental Design for a Rattle, of which the following is a specification, reference being had to the accompanying drawing, forming a part thereof.

In the drawing:

Figure 1 is a front view of a rattle, embodying my new design; and

Figure 2 is a plan view thereof.

I claim:

The ornamental design for a rattle, substantially as shown.

PAUL E. ALLEN.
